ABSTRACT

An improvement in a process for converting an unsaturated, acyclic hydrocarbon to an acid in which the unsaturated, acyclic hydrocarbon is reacted with oxygen containing a small amount of ozone at a low temperature to obtain an intermediate product in a first stage and the intermediate product is oxidized in a second stage with molecular oxygen at a higher temperature to obtain the desired carboxylic acid, which involves heating the intermediate product in the absence of additional oxygen prior to the second stage oxidation, whereby explosive hazards in the second stage are minimized.

PROCESS FOR PRODUCING ORGANIC ACIDS

This invention relates to a process for converting an unsaturated, acyclic hydrocarbon to an organic carboxylic acid by using ozone and oxygen while minimizing explosive hazards associated therewith. More specifically, this invention relates to an improvement in the process wherein an unsaturated, acyclic hydrocarbon is subjected to ozonolysis in a first stage and the product resulting therefrom is subjected to oxidation in a second stage with molecular oxygen to obtain organic carboxylic acids corresponding to said unsaturated, acyclic hydrocarbon.

Unsaturated, acyclic hydrocarbons which can be used herein can be straight or branched chain olefins, terminal as well as internal, having from four to 40 carbon atoms, preferably from six to 30 carbon atoms. Specific examples of olefins that can be used are butene-1, octene-1, undecene-1, eicosene-1, octene-2, dodecene-3, tetradecene-7, nonadecene-8, 3-methylpentene-1, 4-ethyldecene-2, 3-methyl-4-ethyl-nonen-1, etc.

The ozonolysis procedure used in the first step can follow any conventional outline. Thus, for example, a stream of gas containing molecular oxygen, such as oxygen itself, and from about 0.5 to about 6, or even higher, but preferably about 2 to about 3 percent, by weight of ozone relative to oxygen is passed continuously through the olefin charge dissolved in a suitable solvent, for example, a carboxylic acid having from two to ten carbon atoms, such as acetic acid, propionic acid, heptanoic acid and decanoic acid, or an alcohol having from one to six carbon atoms, such as methanol, propanol-1, hexanol-1, etc., at such a rate so that the exit stream will be substantially free of ozone, continuing until some ozone is found in the exit gas, at which time the ozonolysis reaction will have terminated. Since ozonolysis is substantially instantaneous, the time of contact depends upon obtaining suitable contact between ozone and unreacted olefin. The temperature can be from about -20° to about 35° C., preferably about 10° to about 20° C., and while pressures as high as about 50 pounds per square inch gauge can be employed, atmospheric pressure is preferred. As a result of ozonolysis, cleavage of the olefinic double bond occurs and the individual fragments so produced react with ozone and are believed to form aldehydes and hydroperoxides. Thus, the olefin

for example, R' and R'' being alkyl substituents, is believed to be converted to

wherein R''' represents an alkyl group, in the case of an alcohol solvent, and an acyl group, in the case of an acid solvent. The hydroperoxide is believed to result from the addition reaction of the intermediate Zwitterion

with the solvent therein.

The aldehydes and hydroperoxides so produced are then subjected to oxidation in a second stage with a gas containing molecular oxygen, preferably air. Any effective method which insures contact between the aldehyde and the hydroperoxide and oxygen can be used. In a preferred embodiment air is continuously passed through the ozonolysis product and this is preferably continued until there is no noticeable reduction in oxygen content of the exit stream. The amount of oxygen

stoichiometrically needed, relative to the ozonolysis product, defined as consisting essentially of aldehydes and hydroperoxides, on a molar basis must be at least about 1:1, but in general from about 5:1 to about 100:1, is used. Temperatures of about 70° to about 150° C., preferably about 80° to about 110° C., can be used. Pressures as high as about 100 pounds per square inch gauge can be employed, but in general atmospheric pressure is preferred. A reaction time of about 0.5 to about 2 hours will generally suffice. As a result of the oxidation step it is believed the aldehydes are oxidized and the hydroperoxides are rearranged to the corresponding organic carboxylic acids. Recovery of the organic carboxylic acids from the reaction mixture can be effected in any desired manner, but in general fractional distillation is preferred.

Unfortunately, we have found in our studies that during the oxidation in the second stage the vapor phase above the ozonolysis product through which molecular oxygen is being passed has potentially an explosively violent nature. We believe this occurs because the passage of molecular oxygen through the ozonolysis product removes therefrom some of the hydroperoxide therein and the latter forms a mixture with unreacted molecular oxygen that has passed therethrough and it is this mixture that can explode.

We have found that the hydroperoxide content of the ozonolysis product charged to the second stage can be substantially reduced, thereby minimizing the amount thereof that can find its way into the vapor space above the product being treated in the second stage and reducing the explosive character thereof, by heating the ozonolysis product obtained in the first stage in the absence of added oxygen prior to oxidation in the second stage. We believe that such heating converts the hydroperoxide to the corresponding aldehydes and acids.

The latter are the desired acids and the aldehydes so produced, together with the aldehydes obtained in the first stage, are then oxidized to the corresponding acids in the second stage in the manner hereinabove defined. Fortunately, the yield of desired acids is not adversely affected by the heating step.

In conducting the intermediate heating step the ozonolysis product from the first stage, consisting essentially of the defined aldehydes and hydroperoxides, is heated at a temperature of about 95° to about 140° C., preferably about 100° to about 120° C., a pressure of about atmospheric to about 200 pounds per square inch gauge, preferably about atmospheric to about 50 pounds per square gauge, for about 1 minute to about 30 minutes, preferably for about 10 minutes to about 20 minutes. As noted, no oxygen is added to the ozonolysis product during such intermediate heating, and any oxygen which may be present, which does not adversely affect the operation, is that small amount that may be present as a result of entrainment in the first stage, that which may be in the air in the reaction zone or that which may be released in the decomposition of the hydroperoxide. It is critical that the above temperature and time limitations be strictly observed. At lower temperatures, the reaction time necessary for the decomposition of the hydroperoxides becomes too long, whereby the formation of polymers and other by-products is favored. At higher temperatures the decomposition reaction proceeds too violently, thus presenting a potentially hazardous situation in addition to a tendency for formation of undesired by-products.

The process of this invention can further be illustrated by the following.

EXAMPLE I

20 grams of octene-1 were dissolved in 80 grams of 70 propionic acid and the resulting mixture was cooled to a temperature of 4° C. An oxygen stream containing from three to 4 percent by weight of ozone was passed through the mixture over a period of about 3 hours at a rate of about 1 liter per minute while maintaining the temperature of the reaction mixture at 5° to 8° C. The reaction product was found to have a

peroxide number of 2180. By "peroxide number" we mean milliequivalent active oxygen per 1,000 grams of product when determined by an iodometric method. By "active oxygen" we mean the oxygen in the ozonolysis product associated with the hydroxyl group forming the hydroperoxide. The reaction product was then maintained at a temperature of 100° to 108° C. for 60 minutes while air was passed therethrough at a rate of 1 liter per minute. The resulting product was subjected to distillation sufficient to remove propionic acid therefrom. It was found that 94.3 percent by weight of the remainder was heptanoic acid, with substantially the rest being hexanoic acid and neutral compounds.

EXAMPLE II

The run of EXAMPLE I was repeated except that the ozonolysis product at the end of the first stage was heated at a temperature of 100° to 109° C. and atmospheric pressure, in the absence of additional oxygen, over a period of 15 minutes, prior to treatment in the second stage. The peroxide number of the heated mixture was 355. The final product was found to contain 94.3 percent by weight of heptanoic acid, with the remainder being substantially hexanoic acid and neutral compounds.

EXAMPLE III

20 grams of tetradecene-7 were dissolved in 80 grams of propionic acid and the resulting mixture was cooled to a temperature of 4° C. An oxygen containing from three to 4 percent by weight of ozone was passed through the mixture over a period of 100 minutes at a rate of about 1 liter per minute while maintaining the temperature of the reaction mixture at 7° to 9° C. The reaction product was found to have a peroxide number of 2120. The reaction product was then maintained at a temperature of 100° to 108° C. for 60 minutes while air was passed therethrough at a rate of 1 liter per minute. The resulting product was subjected to distillation sufficient to remove propionic acid therefrom. It was found that 92.2 percent of the remainder was heptanoic acid, with acids of lower and higher molecular weight and some neutral compounds as by-products.

EXAMPLE IV

The run of EXAMPLE III was repeated except that the ozonolysis product at the end of the first stage was heated at a temperature of 100° to 108° C. and atmospheric pressure, in the absence of additional oxygen, over a period of 15 minutes, prior to treatment in the second stage. The peroxide number

of the heated mixture was 575. The final product was found to contain 91.9 percent by weight of heptanoic acid. The by-products consisted of acids of lower and higher molecular weight and some neutral compounds.

5 A comparison of the runs in which an intermediate thermal treatment without oxygen was applied with those in which the oxidation step followed the ozonization step immediately shows that the thermal treatment reduces the peroxide content of the mixture to a level which can be considered essentially safe in terms of formation of an explosive mixture in the vapor phase.

Obviously, many modifications and variations of the invention, as hereinabove set forth, can be made without departing from the spirit and scope thereof, and therefore only such limitations should be imposed as are indicated in the appended claims.

We claim:

1. In a process for converting an unsaturated, acyclic hydrocarbon having from four to 40 carbon atoms to an acid wherein the unsaturated, acyclic hydrocarbon is reacted with ozone at a lower temperature of about -20° to about 35° C. to obtain an intermediate product in a first stage and the intermediate product is oxidized in a second stage with molecular oxygen at a higher temperature of about 70° to about 150° C.
- 20 2. The process of claim 1 wherein said heating of said intermediate product prior to said second stage is in the temperature range of about 100° to about 120° C.
3. The process of claim 1 wherein said heating of said intermediate product prior to said second stage is within a period of about 1 to about 30 minutes.
- 25 4. The process of claim 1 wherein said heating of said intermediate product prior to said second stage is within a period of about 10 to about 20 minutes.
5. The process of claim 1 wherein the temperature in said first stage is within the range of about 10° to about 20° C.
- 30 6. The process of claim 1 wherein the temperature in said second stage is within the range of about 80° to about 110° C.
7. The process of claim 1 wherein said unsaturated, acyclic hydrocarbon has from six to 30 carbon atoms.
- 40 8. The process of claim 1 wherein said unsaturated, acyclic hydrocarbon is octene-1.
9. The process of claim 1 wherein said unsaturated, acyclic hydrocarbon is tetradecene-7.
